UNITED STATES PATENT OFFICE

ARTHUR FRICKE, OF DORTMUND, GERMANY, ASSIGNOR TO THE FIRM VEREINIGTE STAHLWERKE AKTIENGESELLSCHAFT, OF DUSSELDORF, GERMANY

WELDED LOCK JOINT FOR SHEET PILING

Application filed February 24, 1932, Serial No. 594,854, and in Germany June 20, 1931.

In the lock-joints for sheet-piling there occur always stresses, independently from the fact whether the lock-joint is placed in the neutral axis or in the outer layer. Shifting, 5 or torsional movements of the sheets, one in relation to the other, however, influence the resistance coefficient of the wall. For reasons relating to the processes of rolling and ramming, it is however impossible to avoid 10 lock-joints altogether. In most cases it is possible to ram two or three sheets locked together. The joints of such a unit which is to be rammed at one and the same time, can be made by welding or by some other means. 15 In the case of welding, however, it has been found that the play-room which every lock-joint must have for reasons related to the rolling process, is a disadvantage. In order to bridge over this play-room, the welding 20 must be extensive and in the welded seam there occur stresses due to shrinking which often give rise to crevices in the seam.

The present invention eliminates these disadvantages in that the play-room is bridged 25 over by a wedge or a flat piece of iron. The wedge is driven in, until the inner lock-parts come to lie entirely one against the other. The wedge is then welded to both sheets. This connection eliminates any longitudinal 30 or transverse displacement and any torsional movement in the lock-joint. The wedges and the welded seams need be arranged only at given distances one from the other. In order to avoid tensional stresses in the welded seam, 35 counter-wedges can be driven in, on the opposite side, at greater intervals, and these counter-wedges can also be welded on.

In the accompanying drawing an embodiment of the invention is represented, of which 40 drawing

Figure 1 shows one form of the lock-joint, and

Figure 2 shows another form of the lock-joint.

In Figure 1 the sheets *a* and *b* are held together, for example, by a Larssen-lock. The wedge *c* is positioned in the space-room between the lock-parts and connected thereto by the welded seams *d* and *e*.

In Figure 2 a counterwedge is arranged be-

sides the wedge on the opposite side of the lock-joint in the space-room between the lock-parts and connected thereto in the same manner as the first mentioned wedge by two welded seams, so that a rigid lock-joint without tensional stresses is obtained. 55

What I claim and desire to secure by Letters Patent of the United States is:

1. A rigid lock-joint of sheet piles, consisting of engaged lock-parts, additional 60 pieces positioned in the natural space-room between the lock-parts, and welded seams connecting the additional pieces to the lock-parts.

2. A rigid lock-joint of sheet piles, consisting of engaged lock-parts, wedge-shaped additional pieces positioned in the natural space-room between the lock-parts, and welded seams connecting the additional pieces to the lock-parts. 65

3. A rigid lock-joint of sheet piles, consisting of engaged lock-parts, additional pieces positioned at either side of the lock-joint in the natural space-room between the lock-parts, and welded seams connecting the additional pieces to the lock-parts. 75

4. A rigid lock-joint of sheet piles, consisting of engaged lock-parts, wedge-shaped additional pieces positioned at either side of the lock-joint in the natural space-room 80 between the lock-parts, and welded seams connecting the additional pieces to the lock-parts.

5. A rigid lock-joint of sheet piles, consisting of engaged lock-parts, wedge-shaped 85 additional pieces positioned in the natural space-room between the lock-parts, and welded seams at either side of the additional pieces connecting the additional pieces to the lock-parts. 90

6. A rigid lock-joint of sheet piles, consisting of engaged lock-parts, wedge-shaped additional pieces positioned at either side of the lock-joint in the natural space-room 95 between the lock-parts, and welded seams at either side of the additional pieces connecting the additional pieces to the lock-parts.

7. Sheet piling composed of locked piles having additional pieces positioned in the 100

natural space-room between the lock-parts and welded to the lock-parts.

8. Sheet piling composed of locked piles having additional pieces positioned at either side of the lock in the natural space-room between the lock-parts and welded to the lock-parts.

In testimony whereof I affix my signature.

ARTHUR FRICKE.
